A. Bligham,
Attorney.

UNITED STATES PATENT OFFICE.

ELBRIDGE Z. STOWELL, OF TUFTS COLLEGE, MASSACHUSETTS, ASSIGNOR OF TWO-FIFTHS TO WILLIAM F. MACCORMACK, OF MALDEN, MASSACHUSETTS.

BRICK FOR FIRELESS COOKERS.

1,412,717.

Specification of Letters Patent. Patented Apr. 11, 1922.

Application filed April 1, 1921. Serial No. 457,669.

To all whom it may concern:

Be it known that I, ELBRIDGE Z. STOWELL, a citizen of the United States, and a resident of Tufts College, in the county of Middlesex and Commonwealth of Massachusetts, have invented certain new and useful Improvements in Bricks for Fireless Cookers, of which the following is a full, clear, and exact specification.

- 10 In fireless cookers, as is well known, the heat for the baking and stewing is received from a hot object usually designated as a "brick" but in reality a block of soapstone, introduced within the non-conducting box.
- 15 The main trouble found in connection with such blocks is their failure to give out heat at a sufficiently high temperature and for a sufficiently long time to properly cook many kinds of food.
- 20 The object of my invention is the production of a brick which shall overcome this objection and will, therefore, continue to supply heat of a high temperature throughout a period much in excess of what has
- 25 previously been the case.

In accomplishing this, I take advantage of the latent heat evolved during the change of a fluid to a solid, and thereby add materially to the heat emitted by the simple cooling of the body. The difficulty, however, is the discovery of a substance which changes from solid to liquid at a temperature proper for cooking, but does not, on the other hand, vaporize at a temperature so low as to render such a process possible during the heating of the brick; for did such vaporizing occur, either the material would escape, or the receptacle be burst thereby. Further, it must not decompose by frequent use, and, finally, it must not be too expensive for family use.

After considerable study and experiment, I have discovered that a certain waste product resulting from the production of aniline dyes from coal-tar, termed phenanthrene, a hydrocarbon whose chemical formula is $C_{14}H_{10}$, and which is graphically represented as follows:

- 50 55 The melting point of this by-product is

approximately 120° C., or about 248° F., and consequently a good cooking temperature, so that after it has cooled down enough to solidify, it gives out a large amount of heat during the process. Further, this 60 latent heat is far in excess of most other substances which might in some ways be available, and hence the material is ideal in this direction also.

The boiling point of this phenanthrene, 65 moreover, is found to be approximately 330° C., and consequently at too high a temperature to be reached by a gas stove such as is used for heating fireless cooker bricks. It is in no danger, therefore, of vaporizing and 70 causing loss of its own substance, or of exploding the container.

Inasmuch as this by-product possesses no other known value, but is a waste in the manufacture of certain aniline dyes, its cost 75 is almost nothing.

I have further found that continued heating and cooling of this phenanthrene fails to decompose it or otherwise render it unfit to perform its required function.

80 Since it liquefies at a comparatively low temperature,—or only 36° F. above the boiling point of water,—it is necessary to confine it in a fluid-tight jacket, as set forth in the accompanying drawings, in which Fig. 85 1 is a plan view of brick embodying my invention, and Fig. 2 is a side sectional view of the same.

The jacket 1 is illustrated as circular to conform to the fireless cookers now on the 90 market, and is preferably composed of aluminum because of its lightness and non-corrosive nature, and more especially because of its high specific heat. To ensure the free conductivity of heat from the material 4 to the exterior of the container 1, I prefer to provide the latter with several ribs 5 reaching far into the material, and being of the same material aluminum, well adapted for the purpose.

100 The jacket 1 and its ribs 5 may be cast complete with a cover 6, an opening 2 closed by a screw plug 3 being provided for the removal of the core used in the casting, and for pouring the material 4 therein.

105 The phenanthrene as it comes from the dye-works is a mass of flakes, but, by first heating it to its melting point, it can be poured into the jacket until full, and then the plug 3 screwed firmly in place.

110

As I have determined by repeated experiment, this brick absorbs and gives out a far larger amount of heat than is delivered by a soapstone body of equal size, inasmuch as 5 it yields thirty-five calories per gramme during its solidification additional to all the thermal units incident to its cooling, both while a fluid and while solid.

What I claim is:

A brick for fireless cookers and the like, 1 comprising a jacket containing phenanthrene.

In testimony that I claim the foregoing invention, I have hereunto set my hand this 29th day of March, 1921.

ELBRIDGE Z. STOWELL.
